UNITED STATES PATENT OFFICE.

ROMAN ABT, OF BÜNZEN, SWITZERLAND, ASSIGNOR OF ONE-HALF TO
OTTO GRUNINGER, OF NEW YORK, N. Y.

RACK-RAIL FOR RAILWAYS.

SPECIFICATION forming part of Letters Patent No. 349,624, dated September 21, 1886.

Application filed April 13, 1886. Serial No. 198,677. (No mod. 1.)

To all whom it may concern:

Be it known that I, ROMAN ABT, of Bünzen, in the Republic of Switzerland, have invented a new and useful Improvement in Rack-Rails for Railways, of which the following is a specification.

My invention relates to a rack-rail which is to be secured upon a road-bed of a railway between ordinary supporting-rails, and with 10 which engages a pinion or pinions upon the locomotive, for the purpose of propelling trains along steep gradients, which could not be propelled with the ordinary adhesion-locomotives. Such a system of driving might be employed 15 in connection with the ordinary adhesion-drivers, the locomotive being propelled along level ground or slight gradients by adhesion only, and the rack-rail and pinion or pinions being employed upon the steeper gradients. In order 20 to enable such compound system to be successfully used, it is necessary that the pinion or pinions of the locomotive or cars should pass into engagement with the rack-rail while the locomotive is running; and the principal 25 object of my invention is to provide an entering rack-rail section with which the pinion or pinions on the locomotive or cars will come easily and without injurious shock or jar into engagement, and from which the pinion or 30 pinions may pass easily and without shock or jar into engagement with the main rack-rail, which will be ordinarily rigidly supported.

To accomplish the desired results I employ, in connection with a locomotive or vehicle 35 comprising a pinion which is preferably arranged to turn independently of the adhesion or supporting wheels, and also in connection with the ordinary supporting-rails, an entering rack-rail section which has a yielding support, so that it may yield to the action of the pinion as the pinion comes into engagement with it, the pinion being meanwhile capable 40 of turning independently of the supporting-wheels, so that the latter will not be compelled 45 to slip or slide on the supporting-rails to permit the proper engagement of the pinion with the rack-rail. The turning of the pinion independently of the supporting-wheels and the yielding of the entering rail both contribute 50 to the easy engagement of the pinion with the rack-rail, and such engagement of the pinion

with the rack-rail preferably takes place while substantially all the weight of the locomotive or vehicle is sustained by the adhesion or supporting wheels bearing on the ordinary adhesion or supporting rails. I hinge the entering rack-rail section to the main rail by means of links or bars which are pivotally connected with them at points near their adjacent ends, as hereinafter described.

To still further facilitate the engagement of the pinion or pinions of the locomotive with the entering rack-rail section, I make the teeth of the entering rail-section of gradually-diminishing depth and vanishing toward the entering end thereof, and I also make the teeth where they are of diminishing depth more rounded in form, so that they finally disappear at the entering end of the rail-section in a wavy or undulated line. I also may make 70 the teeth in the entering rail-section and throughout the whole or part of its length, of abnormal pitch relatively to the teeth of the fixed rail-section, such abnormal pitch being preferably greater than the normal pitch 75 for a purpose hereinafter described. The entering end of the rail-section I bow or curve downward, so that chains or other articles depending from the passing trains will not catch thereon. The springs for supporting 80 the rack-rail section may be applied in any suitable way. I may, for example, provide supports for the rack-rail section which extend through and are guided in the sleepers supporting the adhesion-rails, and the springs 85 may be applied below the sleepers to bear at one end against such supports, which are guided in the sleepers, and at the other end upon base-plates below the sleepers.

The invention consists in novel combinations 90 of parts and features of construction, which are hereinafter described, and pointed out in the claims.

In the accompanying drawings, Figure 1 is a side elevation of an entering rack-rail section 95 embodying my invention, and a portion of the main rack-rail section, including, also, a transverse section of sleepers, which support adhesion-rails and extend under the rack-rail. Fig. 2 is a plan of the parts shown in Fig. 1. Fig. 3 is a transverse section of the rack-rail and adhesion-rails, and showing more clearly

the sleepers which support the adhesion-rails and the spring-support for the rack-rail; and Fig. 4 is a longitudinal section of a portion of a locomotive such as is shown in my Letters 5 Patent No. 339,831, dated April 13, 1886, and having two pinions, which are in engagement with the entering rack-rail section.

In order to avoid making the drawings upon a greatly-reduced scale, I have represented 10 Figs. 1 and 2 upon two sheets, each sheet showing half of the length of each figure, and lettered 1' and 2' on Sheet 2.

Similar letters of reference designate corresponding parts in the several figures.

15 My invention is applicable to rack-rails of the ordinary or other suitable construction; but I now prefer to employ a rack-rail such as is shown in my United States Letters Patent No. 284,790, and which is composed of two or 20 more toothed bars arranged parallel with each other, and having their teeth stepped or in staggered relation to each other. By thus arranging the rack-bars, and by making the pinion or pinions of a number of toothed disks 25 arranged side by side with their teeth stepped or staggered in a like manner, as shown in my said Patent No. 339,831, the working of the pinion in the rack-rail will be much smoother and a stronger and steadier hold will be af- 30 forded.

A designates the main rack-rail section, which is rigidly supported upon the sleepers B, here represented as of metal; and A' designates the entering rack-rail section, below which extends sleepers B', also represented as of metal. 35 The sleepers B' serve to support the adhesion-rails C of the railway, as represented in Fig. 3, and they also support the main rack-rail section A. The rack-rail is composed of two or 40 more parallel toothed bars, three bars being here shown. The bars a, which compose the main rail-section, are held at proper distance apart and secured by rivets or bolts to chairs D, which rest upon the sleepers B. The toothed bars a', which are comprised in the entering rail-section A', have bars or pieces b interposed between them, as shown in Fig. 3, the rack-bars and the bars or pieces b being rigidly secured together by rivets c, or otherwise. 45 The bars or pieces b have laterally-extending flanges b', and are secured by rivets c', or otherwise, to a sole-plate, d. The several parts a b b' d, when secured together in the manner described, form together a strong rail-section. 50 As best shown in Fig. 2, the teeth of the several rack-bars a a' are out of line or staggered in their relation to each other, and as shown in Fig. 1 the teeth of the entering rail-section A' gradually diminish in depth toward the entering end thereof, and are also of more rounded form than the remainder of the teeth, the teeth vanishing toward the entering end of the section A' in a wavy undulated line. The entering ends a' of the rack-bars a' are curved down- 55 ward to the surface of the ground, so that chains or other articles depending from a train will not catch upon them, and the sole-plate

and the flanged spacing-bars b and sole-plate d are or may not be continued clear to the entering end of the rack-bars.

In order to afford the entering rail-section A' a yielding support, I have represented springs E, which are arranged in pairs below it, as shown in Fig. 3, but may be of any suitable character. The springs here shown are 75 of volute form, and are supported at their lower ends on base-plates F, which may be placed upon a suitable beton or other foundation, G.

The rail-section A' is supported directly by 80 means of thimbles or sleeves e, which slide freely within sockets or holes b', provided for them in the sleepers B', and are guided by such sleepers in their rise and fall. Bolts f pass from the rail-section A' downward through 85 the thimbles or sleeves e, the sleepers, and through the base-plates F, and the springs E surround these bolts and bear at their upper ends against the lower ends of the thimbles or sleeves e, and at their lower ends upon the 90 base-plates F.

In order to maintain the proper relation between the adjacent ends of the spring-supported entering rail-section A' and the main rail-section A, which is rigidly supported, I 95 hinge the entering rail-section at its end, and as here represented this hinge-joint is formed by means of parallel links or bars H, arranged on opposite sides of the rack-rail and pivotally connected at their ends g g' with the main 100 rail-section A and the entering rail-section A'.

As shown in Fig. 2, the break or gap S between the several toothed bars of the two rail-sections A A' is made in the tooth-spaces of each bar, and is staggered or set out of line in 105 the several bars.

As represented in Fig. 4, I designates two pinions of a locomotive which have just come into proper engagement with the entering rack-rail A'. In this figure, J designates the 110 main axles, through which and the adhesion-wheels J' approximately all of the weight of the locomotive is supported upon the ordinary adhesion or supporting rails, C. The pinion-axles I are here shown as journaled in a frame, J', hung from the main axles J, and these axles I are coupled together by cranks i and parallel rods i'. The pinions I are driven through rods K from rock-shafts K' K'', arranged one within the other and provided with arms K', 115 to which the rods K are connected, and with other arms, K'', to which power is imparted by rods K' from a pair of cylinders supported from the main cylinders, which impart motion to the adhesion-drivers A'. All these features of construction may be as shown in my afore- 120 said Patent No. 339,831, and as the pinions I can turn independently of the adhesion supporting-wheels J' the engagement of the pinions with the yielding rack-rail section A' is 125 greatly facilitated. The easy entrance of the pinions I into the entering rack-rail section A' is also facilitated by the gradual diminishing 130 depth of the teeth toward the entering

end. When the pinion I strikes the entering rack-rail section, the teeth of the pinion may, by chance, either at once interlock properly with the teeth of the rail, or, if not, they will 5 place themselves directly upon the teeth of the rail, the latter yielding on account of its spring-support. If the pinion should now, without turning, slide over the teeth of the entering rail, which it may readily do if it 10 does not turn in unison with the adhesion-wheels I', then it could only slide a very short distance before its teeth would drop in between the teeth of the rail, and the rail being lifted instantly by its springs the proper interlocking of the pinion and rail would be assured. If, on the contrary, the pinion, by 15 reason of the friction between itself and the rail upon which it rests, should revolve as the locomotive moves ahead, then it would roll 20 upon the teeth of the entering rail, and as its outside diameter is much larger than the pitch-line diameter the relative position between the teeth and those of the rail would change constantly in such a manner that the 25 teeth of the pinion would come into engagement with the teeth of the rail after the pinion had made a part of a revolution. It will be observed that the yielding rail-section A' is guided laterally by the ties or sleepers B', 30 through which pass the sleeve supports e, and which guide the sleeve-supports in their upward and downward movement.

In the use of a locomotive with the entering rack-rail section herein described the pinion 35 will usually have no power transmitted to it until it is in engagement with the main rail-section, and hence the pinion will be free to turn while coming into proper engagement with the yielding rail-section.

40 Instead of springs E, for raising the entering rail A', I may employ weights, which would be the full mechanical equivalent of the springs in the combinations comprising them.

In rack-rail locomotives of small traction, 45 when there is only a single driving pinion, it may be preferred, instead of having a separate set of steam-cylinders for operating the pinion, to work the same conjointly with the adhesion-drivers, to which it would be coupled, 50 (the diameters of the adhesion drivers and the pitch-line diameter of the pinion being in such a case of the same size.) As the pinion then has a fixed positive motion together with the adhesion-drivers, it cannot either rotate freely 55 or slide, and so find its correct contact in the entering rail having its teeth of the same pitch as the main rail-section, as has been described. If the pinion, for instance, should happen to 60 meet the entering rail in such a position that one of its teeth should come to rest immediately on top of one of the teeth of the entering rail, depressing the latter on its springs, it would be impossible for the pinion, on account of the rigid connection with the adhesion-drivers, while passing over the entering 65 rail to effect a change in its relative position to the teeth of the entering rail. It would

simply continue to roll on top of the teeth of the latter. To enable the pinion even in such a case to come into proper contact, I construct 70 all or a portion of the teeth of the entering rail with an abnormal pitch, which may be greater than the pitch in the main rail-section A. If the pitch or the distance measured on the pitch-line between the centers of two 75 adjacent teeth on the entering rail is, for instance, one sixteenth ($\frac{1}{16}$) of an inch larger than the normal pitch of the pinion and of the fixed portions of the rack-rail, it will be obvious that while the pinion continues to roll on 80 top of the teeth of the entering rail its relative position to these teeth is changed by one-sixteenth ($\frac{1}{16}$) of an inch for each abnormal-pitch division traveled over. After having traveled a certain distance, or having passed a certain 85 number of cogs, the aggregate of all the relative changes in position will bring some tooth of the pinion directly between two teeth of the entering rail, which latter will then be forced upward by the springs. The pinion being thus 90 engaged in the entering rail, though not yet necessarily in proper contact, will soon force the adhesion-drivers, on account of its rigid connection with them, to slip on their supporting-rails, and for each subsequent pair of cogs 95 between which an abnormal pitch exists the slipping is repeated to the full extent of each individual abnormality until the normal pitch is reached, when a correct contact will continue. The abnormality may either be uniform 100 throughout the portion over which it extends, or it may be gradually increasing toward the entering end of the rail A' until a certain yet admissible limit is reached. The entering rack-rail, and especially that portion of it over which 105 the abnormal pitch extends, must be made of sufficient length so that the aggregate amounts of the abnormalities will insure the interlocking of the pinion under the most unfavorable conditions under which the pinion may first meet 110 the entering rail. In this case I prefer to make the teeth of the entering rail of a uniform height throughout, in order to eventually get an effective hold in the rack-rail right from the start. 115

In Fig. 1 I have represented the teeth of abnormal pitch by dotted lines as of full height, and the dotted lines o' designate the centers of these teeth, and indicate their abnormality as increasing toward the entering end of the entering rail A'. 120

What I claim as my invention, and desire to secure by Letters Patent, is—

1. The combination, with a locomotive or vehicle comprising a pinion which is arranged 125 to turn or yield independently of the adhesion or supporting wheels, of an entering rack-rail which has a yielding support, so that it may yield to the action of the pinion as the pinion comes into engagement with it, the pinion 130 being meanwhile capable of turning or yielding independently of the adhesion or supporting wheels, substantially as herein described.

2. The combination, with the adhesion or

- supporting rails C, of a rack-rail comprising a yielding entering section arranged in such relation to the adhesion or supporting rails as to receive into engagement with it a pinion or pinions on the locomotive or vehicle, while approximately the whole weight of the locomotive or vehicle is sustained by the adhesion or supporting rails, substantially as herein described.
- 5 3. The combination, with a main rack-rail section, of a spring-supported entering rack-rail section and links H, pivotally connected with both rail-sections at their adjacent ends, substantially as herein described.
- 10 4. An entering rack-rail section having its teeth gradually diminishing in depth and vanishing toward the entering end; substantially as herein described.
- 15 5. An entering rack-rail section having its teeth gradually diminishing in depth and vanishing in wavy undulations toward the entering end, substantially as herein described.
- 20 6. An entering rack-rail section having its teeth diminishing in depth and vanishing toward the entering end, and having its entering end curved downward to prevent any articles depending from a train from catching thereon, substantially as herein described.
- 25 7. The combination, with a fixed or main rack-rail having its teeth of normal and uniform pitch, of a yielding entering rail comprising teeth of abnormal pitch relatively to the teeth of the fixed or main rail, substantially as and for the purpose herein described.
- 30 8. An entering rack-rail section having its teeth of gradually-increasing pitch through-

out a portion of its length at its entering end and in a direction rearward toward its entering end, substantially as herein described.

9. The combination, with an entering rack- 40 rail section having its teeth diminishing in depth toward the entering end, of springs whereby said rail-section is supported, substantially as herein described.

10. The combination, with adhesion-rails 45 and sleepers supporting them, of an entering rack-rail section, supports therefor movable vertically and guided in the sleepers, and springs applied to said supports below the sleepers, substantially as herein described. 50

11. The combination, with adhesion-rails and sleepers supporting them, of an entering rack-rail section, base-plates arranged below the sleepers, bolts extending from the rail-section downward through the sleepers and base- 55 plates, thimbles or sleeves surrounding the bolts guided in the sleepers and supporting the rail-section, and springs surrounding the bolts between the thimbles or sleeves and base-plates and giving yielding support to 60 the rail-section, substantially as herein described.

12. The entering rack-rail section composed of the rack-bars a', the spacing-bars b, interposed between the rack-bars and having laterally-extending flanges, and the sole-plate d, to which said flanges are secured, substantially as herein described. 65

ROMAN ABT.
